OVERHEAD TRAVELING CRANE.

1,415,163.

Specification of Letters Patent.

Patented May 9, 1922.

Application filed July 23, 1918. Serial No. 246,388.

To all whom it may concern:

Be it known that we, LAWRENCE ENNIS and ALEXANDER JACK, both subjects of the King of Great Britain, residing, respectively, in Linthorpe, England, and Motherwell, Scotland, have jointly invented certain new and useful Improvements Relating to Overhead Traveling Cranes, of which the following is a specification.

10 The invention relates to overhead traveling cranes provided with the usual cross traversing and longitudinal movements and in which the lifting appliances are carried by a vertical mast adapted to rotate in a 15 complete circle about its central vertical axis.

According to the invention a cross runway girder fixed to the mast is provided with means for displacing the gripping appliances along the length of the girder to suit the dimensions and configuration of the material to be handled.

In one form of construction two or more lifting crabs with hoisting gear, are adapted 25 to move on suitable tracks along the cross girder and are capable of being racked out and in simultaneously or independently, so that they may be symmetrically placed in relation to the axis of rotation and equalize 30 or balance the distribution of the load.

Each crab may be provided with its own hoisting and racking motors, or one motor may be arranged to operate more than one crab.

35 The plates, bars, or other materials are lifted by electromagnets attached to the hoisting gear of the lifting crabs, or by slings, hooks, dogs, or other gripping appliances, the points of suspension being so distributed that long plates or bars can be 40 lifted in an approximately flat or straight condition.

In a modified construction the magnets or other gripping appliances are suspended 45 directly from the several trolleys and are hoisted or lowered simultaneously by hoisting or lowering the mast and cross runway girder by means of suitable lifting gear on the main trolley. The mast is in this case 50 rigidly guided in its vertical movements. This type is more especially adapted for handling plates or bars in relation to a shearing or other operating machine where greater rigidity and precision of handling

are necessary than is possible with a load 55 suspended by ropes or chains.

In this arrangement the magnets or other gripping appliances may be carried by jointed link-bars, permitting the extension or contraction of the lifting points to suit 60 the length of the material handled, so as to maintain it in a flat or straight condition as already explained.

The accompanying drawings represent examples of constructions according to the 65 invention; Fig. 1 shows a cross runway girder fixed to a vertical mast which is capable of rotation about its central vertical axis, but is not raised or lowered. In the arrangement shown in Fig. 2 the vertical 70 mast can be raised and lowered and also rotated about its vertical axis.

Referring to Fig. 1, 1 represents one of the overhead girders on which run wheels 2 of the frame 3 which serves as a support 75 and guide for the rotary mast 4. Wheels 5 of the frame 3 run on the under side of a lower girder 6. The mast 4 which, in the example shown is of square section, is rotated by a toothed ring 7 gearing with a 80 pinion 8 and connected by shafting 9, wheel 10 and pinion 11 with a worm drive 12 actuated by a motor 13. A collar 14 on a hollow shaft 15 rests on a top girder 16 of the frame 2; the shaft 15 carries the lower 85 part of a ball race 17, the upper part of which is secured to a cross runway beam 18 of the mast 4. The shaft 15 is preferably hollow to convey the electric leads to the motors carried by the cross girder 20 and is 90 guided in bearings 19. Rollers 21 in contact with a circular ring 22 of the frame 3 take up any lateral stresses due to unequal distribution of the weights lifted.

Gripping appliances 23, preferably elec. 95 tromagnets, are secured to the girder 20 and are adapted to be racked to and fro on tracks 24 by wheels 25 driven by reducing gear from motors 26. Motors 27 raise and lower the gripping appliances 23 through 100 suitable gearing.

As explained above the crabs may be racked simultaneously so as to balance the load and the motors may be arranged to operate more than one crab.

In the construction shown in Fig. 2 the square sectioned vertical mast 28 is guided in its up and down movements in the frame

29 and is suspended by wire ropes 30 passing round pulley wheels 31 mounted on a transverse girder 32 guided in the frame 29. The wire ropes 30 wound on drums 31^a are 5 operated by suitable reduction gearing indicated at 33 driven by a motor 34.

The mast 28 is supported by a ball bearing 36 and is guided in the toothed ring 37 which is rotated by pinion 8, shaft 9, 10 and wheel 11 as described in connection with Fig. 1.

Gripping devices 38 are supported by a system of jointed bars, of the lazy tongs type, so disposed that the devices can be 15 moved nearer together or farther apart, while the surfaces remain coplanar. The outer links 40, 41 are pivoted respectively at 42 and 43. The links 44, 45 are pivoted respectively to nuts 46, 47 engaging with a 20 bar 48 of which the screwthread is left-handed at one end and right-handed at the other end. The bar is mounted in a cross-head 49 and is rotated by a wheel 50. Links 51, 52 are pivoted at 53 to the central part 25 of the cross head 49.

Having thus described the nature of the said invention and the best means we know of carrying the same into practical effect, we claim:—

30 1. An overhead crane comprising an overhead trolley and a vertical frame secured to said trolley, a mast suspended from said trolley, a ring secured to said frame, means for rotating said mast and guiding it in said 35 ring, a cross runway girder fixed to and rotating with said mast and symmetrically disposed on each side thereof, hoisting and gripping appliances carried by said cross runway girder on each side of said mast and 40 means for displacing said appliances along the girder.

45 2. An overhead crane comprising an overhead trolley and a vertical frame secured to said trolley, a mast suspended from said trolley, a ring secured to said frame, a toothed ring on the mast, a pinion engaging with said toothed ring and means for rotating said pinion, a cross runway girder fixed to and rotating with said mast and symmetrically disposed on each side thereof, 50 hoisting and gripping appliances carried by said cross runway girder on each side of said mast and means for displacing said appliances along the girder.

55 3. An overhead crane comprising an overhead trolley, a mast suspended therefrom, a cross runway girder fixed to and rotating with said mast and symmetrically disposed on each side thereof, hoisting and gripping appliances carried by said cross runway 60 girder and means by which the said hoisting and gripping appliances can be simultaneously displaced together on the cross runway girder to balance the distribution of the 65 load.

4. An overhead crane comprising an overhead trolley and a vertical frame secured to said trolley, a mast suspended from said trolley, means for rotating said mast, said means comprising a toothed ring surrounding a cross section of said mast and gearing secured to said frame and meshing with said ring, a cross runway girder fixed to and rotating with said mast and symmetrically disposed on each side thereof, hoisting and 70 gripping appliances carried by said cross runway girder and means for displacing said appliances along said girder.

5. An overhead crane comprising an overhead trolley, a mast suspended therefrom, a cross runway girder fixed to and rotating with said mast and symmetrically disposed on each side thereof, hoisting and gripping appliances carried by said cross runway girder and a system of jointed rods connected in the manner of lazy tongs pivoted to said vertical mast and to said gripping appliances, adapted when expanded or contracted to maintain a symmetrical distribution of the lifting points over the object to 85 be lifted.

6. An overhead crane comprising an overhead trolley, a mast suspended therefrom, a cross runway girder fixed to and rotating with said mast and symmetrically disposed on each side thereof, hoisting and gripping appliances carried by said cross runway girder, and means for raising and lowering 90 said mast.

7. An overhead crane comprising in combination an overhead trolley, a square sectioned vertical mast suspended therefrom, a vertical guiding frame secured to said overhead trolley, a transverse girder guided in said frame and secured to said vertical mast, means for raising and lowering said mast and transverse girder, means for rotating said mast about its central axis, a cross runway girder fixed to and rotating with said mast, hoisting and gripping appliances on said cross runway girder and means for displacing said appliances along 100 said cross runway girder.

8. An overhead crane comprising an overhead trolley and a square sectioned vertical mast suspended therefrom and rotatable about its vertical axis, a vertical guiding frame secured to said overhead trolley, a transverse girder guided in said frame, pulley wheels on said transverse girder, 115 drums mounted on the head of said mast, ropes passing round said pulley wheels and said drums, a cross runway girder fixed to and rotating with said mast, hoisting and gripping appliances on said cross runway girder 120 and means for displacing said appliances along said cross runway girder.

9. An overhead crane comprising an overhead trolley and a square sectioned mast suspended therefrom and rotatable about its 130

vertical axis, a vertical guiding frame secured to said overhead trolley, a transverse girder guided in said frame, a ball bearing in said transverse girder supporting said mast, means for raising and lowering said mast and transverse girder, a toothed ring at the lower end of said guiding frame adapted to form a guide for said mast and means for rotating said ring, a cross runway girder fixed to and rotating with said mast, hoisting and gripping appliances on said mast and means for displacing said appliances along the cross runway girder.

10. An overhead crane comprising an overhead trolley and a square sectioned mast suspended therefrom and rotatable about its vertical axis, a vertical guiding frame secured to said overhead trolley, a transverse girder guided in said frame, a ball bearing in said transverse girder supporting said mast, means for raising and lowering said mast and transverse girder, a toothed ring

at the lower end of said guiding frame adapted to form a guide for said mast, a pinion meshing with said ring, an electric 25 motor and gear wheels connecting said motor with said pinion, a cross runway girder fixed to and rotating with said mast, hoisting and gripping appliances on said mast and means for displacing said appliances 30 along said cross runway girder.

In testimony whereof we have signed our names to this specification in the presence of two subscribing witnesses.
